UNITED STATES PATENT OFFICE.

JOSEPH HOFFMAN, OF NEW YORK, N. Y., ASSIGNOR TO GUSTAVUS A. GOLDSMITH, OF SAME PLACE.

PENCIL OR CRAYON HOLDER.

SPECIFICATION forming part of Letters Patent No. 326,737, dated September 22, 1885.

Application filed March 12, 1885. (No model.)

To all whom it may concern:

Be it known that I, JOSEPH HOFFMAN, a citizen of the United States, and a resident of New York city, in the county of New York and State of New York, have invented certain new and useful Improvements in Pencil or Lead or Crayon Holders, of which the following is a specification.

My invention relates to that class of pencils or lead and crayon holders in which clamping-jaws (in combination with a sleeve or sheath and a lead or crayon containing tube) are contracted or closed upon or caused to hold the lead or crayon subjected to their action by the movement longitudinally of the sleeve or sheath relative to the jaws, or vice versa; and my invention, more specifically stated, consists in combining, with the above-recited parts, mechanism for holding the lead or crayon both in its projected and retracted position and for feeding the same, this mechanism being placed within the lead-containing tube.

Among the advantages secured by my invention are, first, definite retention of the lead or crayon in its projected position when in use, whereby its backward slipping, consequent upon dulling or weakening of the clamping-jaws or shaving of the lead, is avoided; second, a positive feed without danger of losing the lead; and third, avoidance of the direct nipping action of the jaws upon the lead or crayon, which frequently occasions its fracture.

In the drawings like reference-letters indicate like parts in all the figures.

Figure 1 illustrates a pencil-holder embodying my invention, the external sheath or sleeve, with its trimmings, being shown in longitudinal central section, and the lead-holding mechanism projected ready for use, this mechanism, the tube which contains it, the actuating-spring, and the clamping-jaws being shown in plan view. Fig. 2 illustrates the same pencil-holder shown in Fig. 1, the lead-holding mechanism being retracted, and all the parts being shown in longitudinal central section, with the exception of the lead-holding mechanism, which is shown in plan view. Both of these figures are somewhat enlarged from the size of an actual pencil-holder, the better to illustrate the several parts, their construction and combination.

A is the outer sheath or case. It may be made of wood, metal, rubber, paper, or any other suitable material. In the pencil-holder shown in the drawings it is formed of a tubular hard rubber body, *a*, provided with a metal tip, *b*, which may be contracted at its forward end where it engages with the clamping-jaws. It is attached to the hard-rubber part in any suitable manner.

B is the lead-containing tube or receiver, formed of metal in the present instance, and it should preferably be made of metal, although I do not limit myself to such material. It carries at its front end the clamping-jaws C, which in the instance illustrated are made integral with the body of the tube B. These jaws have normally a slight spring away from each other, so that when projected from the end of the pencil they separate, and are so constructed as to nip or bite the lead or crayon placed between them. They are formed externally with a taper or inclined part, *c*. These parts are so constructed and adjusted to each other that when the jaws are retracted the front end of the sheath (shown at *b*) will act on the inclined surfaces *c* and close the jaws firmly upon the lead or crayon holding device projecting between them, the end of the jaws being outside of the sheath. Encircling the rear end of the tube B is a spiral or other suitable spring, *d*, one end of which bears against the shoulder formed by the forward end, *e*, of a small metal cap, *f'*, fastened on the extreme rear end of the tube B, and the front end of the spring bears against a shoulder, *g*, formed on a sleeve or lining, *h*, attached to the inside of the sheath A, and which projects somewhat beyond the rear end of the sheath A, as seen at *i*, for the sake of giving that end of the sheath a finished appearance. The cap *f'* and the sleeve *h* are both preferably made of metal. The cap *f'* moves with the tube B, which carries the jaws C, sliding smoothly within the sleeve *h*, and at the forward end the metal tip *b* should preferably be so contracted at the part marked *b'* that it will properly guide and support the tube B. The stop K, formed upon the tube B, takes a bearing against the shoulder *g* of the sleeve or lining *h*, and limits the rearward action of the spring *d*. It works in a slot formed in the front end of the sleeve *h*, thus

also preventing rotation of the tube B relative to the sheath A.

Within the tube B is placed the lead-holding mechanism. This consists of the lead-receiving tube and feeding devices of an ordinary propelling-pencil, (shown at F,) and it is provided with the usual rotatable tip, f, which engages with the usual internal tube and follower with threaded exterior, which engages with threads formed on the inside of the outer tube, F, all as usual in propelling-pencils, and which do not require more specific description or illustration here. In one side of the tube B, I form a slot, h², (seen in Fig. 1,) in which travels a lug or ear, h', formed on the rear end of the external tube of the lead-holding device F. This lug is so located on the lead-holding device relative to the slot h that when it is in contact with the forward end or shoulder of the slot the lead held by the holding device will be in its proper projected position, and so that the jaws C will upon their retraction, consequent upon the release of the spring d, close upon the lead-holding device behind a little collar, k', formed on the extreme forward end of the external tube of the lead-holding device, thus securely clamping the same and holding it and the lead held by it firmly in the proper projected position for use; and the slot h² is made of such length that when the lead-holder is retracted it and the projecting end of the lead held by it may drop entirely within the jaws C before the lug h' strikes the back end of the slot. The lug h', in addition to its above-recited function, prevents rotation of the external tube F of the propelling lead-holder upon twisting the tip f for feeding the lead. The lead is shown at X. It is inserted at the front end of the tip f, as usual in propelling-pencils.

The operation is as follows: Assuming the propelling lead-holder to be retracted within the tube B, by pressing on the cap f', the tube B will be pushed forward against the stress of the spring b, thus projecting the jaws C, which then, springing apart, allow the propelling lead-holder bearing the lead to drop, the pencil being held with the lead end down, until the lug h' comes in contact with the forward shoulder or end of the slot h², which stops the lead-holder. The pressure upon the cap f' is then released, and the spring d, retracting the lead tube B, carries the propelling lead-holder F with it until the jaws C, being contracted by the tip b of the sleeve or sheath, close in behind the collar or shoulder k' and securely lock the several devices maintaining the lead firmly held in the propelling-holder F in the

projected position suitable for use. When it is desired to retract the lead, the pencil-holder is held with the lead upward, and pressure is applied to the cap f'. The parts are again acted upon as before. The jaws relax their hold upon the propelling lead-holder, which then immediately drops within the tube B, carrying the lead x entirely within the jaws C until the lug h' comes in contact with the rear end of the slot h². The pressure being then removed from the cap f', the jaws C are again closed, and the lead and its propelling and holding device are all inclosed within the tube B and held therein by closing of the jaws.

It is obvious to one skilled in this art that many changes may be made in the location and relative adjustment of the parts above shown and described, and that various equivalent devices may be used instead of those shown and still my invention be employed. I do not, therefore, limit myself to the details either of construction or arrangement shown.

I claim—

1. The combination, in a lead or crayon holder, of a case or sheath, expanding jaws tapered or provided with projections acted on by the case or sheath to produce the closing of the jaws, and provided with an extension beyond the end of the case opposite the jaws, whereby the jaws may be pressed outwardly from the case, a spring which automatically moves the jaws relative to the case longitudinally, and a lead-holding device provided with a stop or stops to limit its movement inwardly and outwardly, placed between the jaws and retained in place by them both in its extended and retracted position, substantially as and for the purposes set forth.

2. The combination, in a lead or crayon holder, of a case or sheath, expanding jaws acted on by the case or sheath to produce the closing of the jaws and provided with an extension beyond the end of the case opposite the jaws, whereby the jaws may be pressed outwardly from the case, a spring which automatically moves the jaws relative to the case longitudinally, and a lead-holding device placed between the jaws and retained in place by them, both in its extended and retracted position, substantially as and for the purposes set forth.

Signed at New York, in the county of New York and State of New York, this 7th day of March, A. D. 1885.

JOSEPH HOFFMAN.
